CLAIM

The ornamental design for a latex cup cover as shown and described.

DESCRIPTION

FIG. 1 is a front, right and top perspective view of a latex cup cover, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a cross-sectional view of the latex cup cover of FIG. 1, taken along section line 9-9 as depicted in FIG. 3. The broken lines shown in the drawings are included for the purpose of illustrating portions of the latex cup cover that form no part of the claimed design.

1 Claim, 9 Drawing Sheets
